(57) **CLAIM**

The ornamental design for a head member for a chess piece, as shown and described.

DESCRIPTION

FIG. 1 is a front view of a head member for a chess piece showing my new design.

FIG. 2 is a back view of the head member for a chess piece. FIG. 3 is a side view of the head member for a chess piece. FIG. 4 is a top view of the head member for a chess piece; and,

FIG. 5 is a bottom view of the head member for a chess piece.

The broken line shown in FIG. 2 is for illustrative purposes only and forms no part of the claimed design.
